ROCKING FULCRUM FOR ADJUSTABLE AND
PIVOTAL OUTER WRENCH JAWS

Ottavio A. Capra, Jamaica, N. Y.

Application March 10, 1948, Serial No. 14,095

3 Claims. (Cl. 81—105)

1

An object of the invention is to provide a novel fulcrum for an adjustable and pivotal wrench jaw, the fulcrum including upper and lower arcuately slideable blocks, an adjusting nut positioned between the blocks, and a spring interposed between the nut and the lower block in order to prevent accidental rotation of the nut.

Other objects of the invention will become apparent from the following description of a preferred embodiment thereof, reference being had to the accompanying drawing in which:

Figs. 1 and 2 are a side and a rear elevation, respectively, of a pipe wrench according to the invention;

Fig. 3 represents, on a larger scale, a fragmentary cross-sectional elevation taken on line 3—3 of Fig. 2, showing the nut, rocker and nut spring assembly with the hook jaw and loading spring removed;

Fig. 4 is a transverse cross section taken on line 4—4 of Fig. 1;

Fig. 5 is a transverse cross section taken on line 5—5 of Fig. 1;

Figs. 6, 7 and 8 are a top, side and front view, respectively, of either of the rocker members shown in section in Fig. 3;

Figs. 9, 10 and 11 are a top, side and front view, respectively, of the nut spring shown in section in Fig. 3;

Figs. 12 and 13 are fragmentary side elevations, showing certain modifications of the lower jaw of the wrench; and

Fig. 14 is a view similar to Fig. 4 but with the hook jaw and rocker assembly removed, showing a modification of the yoke member forming the support for said jaw and rocker assembly.

The principal parts of the pipe wrench 12 shown in the drawing are a handle 13, supporting the lower or stationary jaw 14, a yoke 15 containing the nut, rockers and spring assembly 16, and the upper or hook jaw 17 supported on the yoke 15 by means of the assembly 16. The assembly 16 comprises, in turn, an upper rocker member 18, a lower rocker member 19, a nut 20 and a nut spring 21, these various elements co-acting with one another and with the threaded shank 22 of hook jaw 17 in a manner presently to be described.

The handle 13 is a hollow piece of tubing or casting which comprises an upper portion 13a of elongated, roughly elliptical cross section (Fig. 4) and a lower portion 13b of circular cross section (Fig. 5), the two portions being separated by a dividing line 23 above which a gradual transition from the configuration shown in Fig. 5 to that

2

shown in Fig. 4 takes place. The greater part of lower portion 13b has a knurled surface, as shown at 24, to afford a better grip for the user.

The handle portion 13b terminates in a flattened end portion 25, the latter being preferably provided with a hole 51 serving to suspend the wrench from a hook or nail when not in use.

The peculiar shape of handle 13 furthermore enables portion 13a thereof to support the lower jaw 14 without the provision of any special fastening means therefor. As best seen in Fig. 3, the jaw 14 is provided with a depending portion or stem 26 which penetrates a certain distance into handle portion 13a, the toothed upper portion 14a of the jaw simply resting on the upper rim of the handle. Stem 26 fits snugly into handle portion 13a, as shown in Fig. 4; if desired, however, the jaw 14 may be readily withdrawn from the handle and just as simply reinserted or replaced.

20 The yoke 15 comprises a frame having two aligned circular cutouts 27, 28, the frame being preferably of oblong, rounded-off cross section generally similar to that of handle portion 13a, and partly embracing the latter as shown in Fig. 4. Frame member 15 forms a vertical channel 29 just wide enough to accommodate the shank 22 of hook jaw 17, this shank being preferably provided with opposite longitudinal tapered grooves 30, 31 to reduce weight and friction. Threads 32 on shank 22 are in engagement with threads 33 of nut 20, the latter projecting through the cutouts 27, 28 but being held clear of the frame 15 by means of rockers 18, 19 and spring 21. The two rockers being identical in construction, only one of them, the upper rocker 18, is shown in detail in Figs. 6, 7 and 8.

25 The rocker 18 comprises a circular base 34 formed with a roughly rectangular cutout 35 whose width corresponds to that of channel 29 in yoke 15. The cutout 35 is bounded by two segmental ridges 36, 37 having a radius of curvature which equals the radius of circular cutouts 27, 28 in yoke 15. Ridges 36, 37 register respectively, with the side walls 38, 39 of the yoke 15 when the members 18, 19, 20, 21 and 22 are operatively assembled, nut spring 21 serving to insure continuous contact between these ridges and adjacent portions of these side walls.

30 Referring to Figs. 9, 10 and 11, it will be seen that the spring 21 comprises a resilient annular member 40 formed with a cutout 41 which registers with cutout 35 in rocker 18 and the corresponding cutout in rocker 19, except for recesses 42 of small radius provided at each of the four corners of cutout 41. The purpose of these re-

cesses is to provide clearance between the spring 21 and the corners of thread 32 so as to prevent any jamming action in the event of misalignments of the spring relative to the shank 22. Spring 21 is further provided with four depending tags 43 which resiliently engage the base 34a of lower rocker 19, as best seen in Fig. 3, whereby longitudinal displacement of the spring 21 sufficient to interfere with the movement of the threaded shank 22 will be prevented. By bearing upon the nut 20, spring 21 also prevents spontaneous rotation of this nut whereby the wrench will be forced to retain a given setting.

From Fig. 1 it will be seen that the toothed portion 17a of hook jaw 17 extends at an angle greater than 90° relative to the shank 22, even as the toothed portion 14a of lower jaw 14 is inclined toward the horizontal in the opposite sense. This arrangement makes it possible to grip for example, a pipe and a fitting or union connected thereto without intervening manipulation of the nut 20. In order to insure secure gripping of the work piece by the jaws 14, 17 in spite of their uncommonly wide angle of opening, a loading spring 44 bears upon the shank 22 above the pivoting center assembly 16, thus tending to rock the hook jaw 17 into closing position.

The spring 44 preferably consists of a resilient blade having a gooseneck portion at 45 which engages the rear wall 47 of yoke 15 from underneath, this wall being provided with a hole 48 into which enters a tag 49 formed at one extremity of spring 44. The other extremity 46 exerts pressure upon the hook jaw 17. It will be seen that the loading spring 44 may be placed in position by simply introducing portion 46 thereof into the channel 38 from below, to the rear of pivot assembly 16, and inserting the tag 49 into the hole 48, no further anchorage as by riveting or other fastening methods being required.

The yoke 15 is preferably secured to handle portion 13a by spot welding. For this purpose, the walls 38, 39 of the frame forming the yoke may be provided with a plurality of projections 50 to insure good conductive and mechanical contact at the points where welding is to take place.

Fig. 12 illustrates a modification of the lower jaw or heel plate, indicated here at 114, designed to provide a better grip on stock of certain sizes. The teeth of this jaw 114 are arranged along a convex surface, the radius of curvature being selected so that pieces of stock 52 will be more effectively accommodated by positioning them adjacent the vertical shank of hook jaw 17, as illustrated.

A particularly improved accommodation of pipes and companion mate fittings especially for larger sizes may be obtained by designing the stationary jaw in the manner shown at 214 in Fig. 13. Here the heel plate comprises a horizontal portion 214a which, therefore, extends at right angles to the axis of the handle 13, as well as an inclined front portion 214b enclosing an angle of less than 90 degrees with said axis. The latter angle may be substantially the same as that of heel plate 14a, Figs. 1 and 3.

Fig. 14 illustrates a yoke member 115 which is a modification of yoke 15, Figs. 1, 3 and 4, in that the sides thereof do not close around the handle portion 13a but remain spaced apart to provide a substantially U-shaped cross section. This en-

ables the member 115 to be stamped and pierced, thereby greatly simplifying the manufacturing process and reducing the cost of the entire wrench.

5 Although the invention has been described and illustrated with particular reference to a single, now preferred embodiment, it is to be distinctly understood that various modifications and adaptations are within reach of persons skilled in the 10 art and may be carried out without departing from the disclosed function or exceeding the scope of the invention as defined in the objects and in the appended claims.

I claim:

1. In a pipe wrench, in combination, a handle, a fixed jaw supported on said handle, a hook jaw comprising a threaded shank, and pivot means supporting said shank in a position offset from and roughly parallel to said handle, said pivot 20 means including a yoke member secured to said handle, said yoke member being formed with a channel to receive said shank and further having a pair of co-extensive circular cutouts communicating with said channel at opposite sides 25 thereof, a nut surrounding said shank and extending into said cutouts, a pair of oppositely disposed segmental rocker members each surrounding said shank above and below said nut, respectively, said rocker members being each slidably held in both of said cutouts, and a bowed plate spring surrounding said shank intermediate said nut and one of said rocker members, said spring moving jointly with said rocker members and with said nut inside said cutouts, whereby 35 both of said rocker members will be forced firmly against said yoke member and spontaneous rotation of said nut will be prevented.

2. The combination according to claim 1, wherein said shank is formed substantially rectangular in cross section and said spring is provided with an approximately rectangular cutout, each of the corners of said cutout being recessed to provide clearance between said spring and the corners of said shank.

45 3. The combination according to claim 1, wherein said spring is provided with a plurality of depending tags resiliently engaging the adjacent rocker member to prevent substantial relative displacement between said spring and said 50 adjacent rocker member.

OTTAVIO A. CAPRA.
